FLORAL ARRANGEMENT FROG OR THE LIKE

Henry J. Marien, Warwick, and James B. Swett, Barrington, R.I., assignors to Rexall Drug and Chemical Company, Los Angeles, Calif., a corporation of Delaware

Filed Mar. 29, 1965, Ser. No. 84,502

Term of patent 14 years

(Cl. D35—3)

FIG. 1

The broken lines are shown for illustrative purposes only.

We claim:

The ornamental design for a floral arrangement frog or the like, as shown and described.
